(57) **CLAIM**

We claim, the ornamental design for a fixing member for bags accessory, as shown and described.

DESCRIPTION

FIG. 1 is a perspective view of fixing member for bags accessory, showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a cross-sectional view taken along the lines A-A of FIG. 2;

FIG. 9 is a perspective view of thereof engaged with a corresponding member of fix member of bags accessory;

FIG. 10 is a perspective view of fixing member for bags accessory;

FIG. 11 is a front view thereof;

FIG. 12 is a rear view thereof;

FIG. 13 is a left side view thereof;

FIG. 14 is a right side view thereof;

FIG. 15 is a top plan view thereof; and,

FIG. 16 is a bottom plan view thereof.

The broken lines showing a corresponding member in FIG. 9 are included for the purpose of illustrating the invention in use, and form no part of the claimed invention.

1 Claim, 16 Drawing Sheets
